CEMETERY MEMORIAL PLAQUE OR THE LIKE

Robert J. Rettman, Pittsburgh, Pa., assignor to Jas. H. Matthews & Co., Pittsburgh, Pa., a corporation of Pennsylvania

Application February 18, 1954, Serial No. 29,091

Term of patent 14 years

(Cl. D79—2)

Fig. 1

To all whom it may concern:

Be it known that I, Robert J. Rettman, a citizen of the United States, residing in Pittsburgh, county of Allegheny and Commonwealth of Pennsylvania, have invented a new, original, and ornamental Design for a Cemetery Memorial Plaque or the like, of which the following is a specification, reference being had to the accompanying drawing, forming part thereof.

The ornamental design for a cemetery memorial plaque or the like, substantially as shown.
